US0D1040227S

(12) **United States Design Patent** (10) Patent No.: **US D1,040,227 S**
De Smet (45) Date of Patent: ** Aug. 27, 2024

(54) **DESK MAT**

(71) Applicant: **Garzini, besloten vennootschap**,
Herzele (BE)
(72) Inventor: **Christophe De Smet**, Herzele (BE)
(**) Term: **15 Years**
(21) Appl. No.: **35/516,138**
(22) Filed: **Jan. 13, 2023**
(80) **Hague Agreement Data**
Int. Filing Date: **Jan. 13, 2023**
Int. Reg. No.: **DM/226279**
Int. Reg. Date: **Jan. 13, 2023**
Int. Reg. Pub. Date: **Feb. 3, 2023**

(57) **CLAIM**

The ornamental design for a desk mat, as shown and described.

DESCRIPTION

1. Desk mat
1.1 : Front, right perspective
1.2 : Back, left perspective
1.3 : Front perspective
1.4 : Right perspective
1.5 : Left perspective
1.6 : Back perspective
1.7 : Front, right perspective
1.8 : Back, left perspective
1.9 : Front perspective
1.10 : Right perspective
1.11 : Left perspective
1.12 : Back perspective
1.13 : Front, right perspective
1.14 : Top perspective
1.15 : Right perspective
1.16 : Left perspective
1.17 : Front perspective
1.18 : Bottom

Figures 1.1 to 1.6 show the center element of the desk mat in a first folded position; Figures 1.7 to 1.12 show the center element of the desk mat in a second folded position; Figures 1.13 to 1.18 show the center element of the desk mat in a flat position.

1 Claim, 18 Drawing Sheets
